UNITED STATES PATENT OFFICE.

EDWARD C. BROWN, OF ROCHESTER, NEW YORK, ASSIGNOR TO THE E. C. BROWN COMPANY, OF ROCHESTER, NEW YORK, A CORPORATION OF NEW YORK.

ATOMIZER.

Application filed September 26, 1925. Serial No. 58,799.

My present invention relates to atomizers and more particularly to those of the type known as "mouth sprays" which however does not necessarily mean an atomizer for spraying the mouth but is generically applied to atomizers in which the air pressure is supplied through a mouth piece that is applied to the lip and blown upon. The invention has for its object to provide a simple, efficient and inexpensive atomizer of this type having improved features of construction wherein, with two parts, the device is simply made and yet will be tight in all its joints and seams. To these and other ends the invention resides in certain improvements and combinations of parts all as will be hereinafter more fully described, the novel features being pointed out in the claims at the end of the specification.

In the drawings:

20 Fig. 1 is a side view of an atomizer constructed in accordance with and illustrating one embodiment of my invention;

Fig. 2 is an enlarged perspective view of the mouthpiece, detached;

25 Fig. 3 is a bottom view.

Fig. 4 is an enlarged section taken on the line four four of Fig. 1 and

Fig. 5 is an enlarged section on the line five five of Fig. 1.

30 Similar reference numerals throughout the several views indicate the same parts.

My improved atomizer operates on the well-known principle wherein a well tube is inserted in an upright position in the liquid to be dispersed and a current of air then blown transversely across the open upper end which creates a partial vacuum in the tube and causes the liquid to rise therein and, in overflowing at the top to be projected in a spray by the blast of air. In the present instance the blast of air is created by the operator blowing through the mouthpiece.

Referring more particularly to the drawings, 1 indicates a preferably seamless well tube that may be inserted in a bottle or other liquid container. The mouthpiece is indicated generally at 2. It comprises a conical tube, flattened at its large end as indicated at 3 and having its small end 4 about the size of 45 the well tube 1 and arranged directly at the mouth thereof to discharge air substantially at right angles thereto although it is preferable that the mouthpiece or air tube should be inclined slightly upwardly so that the blast of air will be directed at a slight up-

ward angle to the course of the liquid as it rises in the tube. The end 3 is of a convenient shape to place between the lips and the blast is concentrated at the small end 4.

The mouthpiece is formed of a single piece 60 of metal. The central portion thereof is rolled and then flattened as described, the edges at the mouthpiece being over-lapped as indicated at 5 in Fig. 3. At the opposite or discharge end, ears are provided which are 65 rolled at right angles to the axis of the mouthpiece to form a socket sleeve 6 that fits closely over the upper end of the well tube 1. These ears constitute extensions on a pair of fins 7 which proceed downwardly from the seam of 70 the mouthpiece tube and the lower edges of which extend at an angle from the lower end of the sleeve 6 upwardly and rearwardly to a point at which they are cut from the lap seam 5 of the lip portion 3. These fins are, 75 therefore, in the nature of a strengthening brace that makes the mouth tube rigid with the well tube 1. A lap 8 on one of the fins is brought over the edge of the other as clearly shown in Figure 4 and provides an air-tight 80 seam at the lower edges of the fin so that the air pressure exerted by the operator is not dissipated before the blast reaches the point at which the atomizing occurs.

The device may thus be constructed of only 85 two parts and of very thin sheet metal but with the result that the parts are both rigidly and tightly connected. By emersing the device in a tin bath the seams heretofore referred to are sealed and in addition the sleeve 90 6 at the mouthpiece is permanently secured to the well tube 1.

I claim as my invention:

1. In an atomizer, the combination with a well tube, of a mouth piece having an atomizing relationship with the upper end of the tube, said mouth piece being formed of sheet material and provided at its seam with a flange having an extension embracing and connecting it to the well tube. 100

2. In an atomizer, the combination with a well tube, and a tubular mouth piece of sheet material having an atomizing relation to said tube, of a pair of flanges extending from the seam of the mouth piece and having 105 tubular extensions embracing and connecting the mouth piece to the well tube.

3. In an atomizer, the combination with a well tube, of a tubular mouth piece of sheet material having an atomizing relation- 110

ship with said well tube, said mouth piece being provided at its seam with two triangular flanges secured together and diverging toward the well tube, the ends of the flanges 5 being provided with portions embracing the tube.

4. In an atomizer, the combination with a well tube, of a mouth piece having an atomizing relationship with the upper end 10 of the tube, said mouth piece being formed of sheet material and provided at its seam with a pair of flanges, having an extension on one of said flanges connecting it to the well tube, one of said flanges having an edge portion 15 extending past the other of said flanges, and bent over the same to form an air tight joint.

5. In an atomizer, the combination with a well tube, of a mouth piece formed from 20 a blank of sheet material and having an at-

omizing relationship with the upper end of the well tube, said mouth piece being provided at its seam with a flange integral therewith which extends laterally from the mouth piece, said flange having thereon an integrally formed 25 sleeve adapted to engage the well tube.

6. In an atomizer, the combination with a well tube, of a mouth piece formed from a blank of sheet material and having an atomizing relationship with the upper end of the well tube, said mouth piece being provided at its seam with a pair of integral, substantially symmetrical flanges extending 30 radially from the mouth piece, said flanges having portions integral therewith extending axially past the end of the mouth piece and 35 formed for engagement with said well tube.

EDWARD C. BROWN.
